(74) Attorney, Agent, or Firm—Haugen Law Firm PLLP

(57) **CLAIM**

The ornamental design for a torsion bar adjustment key, as shown and described.

DESCRIPTION

FIG. 1 is a perspective view of the design;

FIG. 2 is a side elevation view of the design;

FIG. 3 is a front end view of the design;

FIG. 4 is a rear end view of the design;

FIG. 5 is a top plan view of the design; and,

FIG. 6 is a bottom plan view of the design.
